UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed September 8, 1920. Serial No. 408,799.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to devices known as rail anchors or anti-creepers, to prevent the longitudinal creep of railroad rails, and has for its primary object to provide an improved device of this character which will be light in weight, inexpensive to manufacture, strong enough to withstand the stresses to which devices of this character are subject when in service and which will not be loosened in its hold on the rail by vibration or other causes having that tendency.

It is well known that railroad rails, even when made in conformity with the same standard, often vary in the width and thickness of their base flanges. This imperfection may be due to the wearing away of the bearing surfaces of the rolls employed in manufacturing the rails, or it may be due to the corrosion of the rails after they have been in service for some time. Such conditions as these present certain disadvantages in connection with one-piece devices, as ordinarily these devices are not well adapted to be used on rails which vary in the width and thickness of their base flanges.

It is one of the specific objects of my invention to provide a new and improved rail anchor, preferably a one-piece device, which can be used effectively on rails, the base flanges of which may vary in width or thickness. A further specific object is to provide a rail anchor which will check or counteract the various tendencies, such as vibration, counter-creeping, and the like, which operate to cause rail anchors to work loose on the rail. In this connection my invention contemplates the provision of a one-piece rail anchor which will grip the edges of the rail by a hold which increases during the presence of a creeping pressure on the rail.

A further object is to provide a rail anchor which shall be effective against movements or creeping of the rail in either direction.

A further object is to provide a device which may be conveniently and quickly applied or removed from the rail, when desired.

My invention consists in the novel arrangements and constructions to be herein-after described and claimed for carrying out the above stated objects and such other objects as will appear from the following description of certain preferred embodiments which are illustrated in the accompanying drawings, in which:

Figure 1 is a perspective view of the device shown as being applied to the rail.

Figure 2 is a plan view of the device as applied to the rail, and in position against one of the ties supporting the same.

Figure 3 is a perspective view of the rail anchor before application to the rail.

Figure 4 is a side elevation view of the device to illustrate the manner in which it is applied to the rail.

Figure 5 is a view similar to Figure 1, illustrating a modification.

Figure 6 is a plan view of the rail anchor shown in Figure 5.

Figure 7 is a perspective view of the same anchor before application to the rail, and

Figure 8 is a side elevation of the same anchor to illustrate the manner in which it is applied to the rail.

Like characters of reference designate like parts in the several figures of the drawings.

Referring first to Figures 1 to 4 inclusive, 85 10 indicates a railroad rail and 11 one of the cross ties on which the rail is supported.

The rail anchor preferably consists of a single piece of metal cut and bent to the form shown in Fig. 3. I preferably use a 90 flat piece of mild steel. The device is formed so as to provide hook or jaw portions 12 at one end adapted to engage with one of the base flanges of the rail. The other end of the device is provided with hook or jaw portions 13 and 14 which are adapted to engage with the other base flange of the rail. The portions 15 and 16 of the anchor intervening between the jaws 12 and the jaws 13 and 14, respectively, are narrower than the ends 95 of the anchor so that they will extend under the base flanges of the rail. In order to pre-

vent any rocking movement of the anchor on the rail I preferably provide the two jaws 12, one on each side, although it will be obvious from the following description that the anchor will take a very reliable hold on the rail if only one such jaw be provided. The free end of the web portion 16 is formed with an extension 17 to provide a locking tongue adapted to bear against the side of the jaw portion 13. The anchor is preferably made so that the jaws 12 and 13 stand substantially in parallelism with the jaws 12 and 14 when the anchor is free of the rail, the distances between the jaws 12 and 13 and jaws 12 and 14 being somewhat greater than the transverse distance across the rail base. In applying the anchor to the rail base the jaws 13 and 14 have to be forced away from each other which causes at least one and preferably both the web portions 15 and 16 to assume a diagonal position under the rail base. The tongue 17 is then driven into engagement with the jaw 13 to maintain the jaws 13 and 14 in such forced apart position. The jaws 13 and 14 are formed with beveled surfaces 18 and 19, respectively, to facilitate application of the anchor to the rail and the tongue 17 and jaw 13 are formed with beveled surfaces 20 and 21, respectively, to facilitate entry of the tongue into engagement with the jaw 13.

The anchor is applied to the rail as follows: It is placed under the rail with the jaws 12 engaging one edge of one of the base flanges, this position being shown in Fig. 4, and is also indicated by the dotted lines in Fig. 2. The other end of the anchor is then raised, the beveled surfaces 18 and 19 riding over the edge of the other base flange, which brings the jaws 13 and 14 into loose engagement with that base flange. This end of the anchor then is held against downward movement, as by a track bar or other suitable means being placed under the tongue 17, while a wedge 22 is driven between the jaws 13 and 14, as shown in Fig. 1. The wedge forces the jaws 13 and 14 apart and causes all the jaws to take a tight grip on the base flanges. The jaws 13 and 14 are forced apart sufficiently to permit bending of the locking tongue into engagement with the jaw 13 which bending may be done by striking it with a hammer. Since the web portion 16 is considerably narrower in width than the tongue 17, the tendency is for the tongue to bend on or close to the dotted line 23 rather than at the corner 24. The tongue, therefore, describes an arc, with the metal about the lines 23 as its pivot which pivot, it will be observed, substantially coincides with the edge of the base flange. The web portion 15 and its jaw 13 stand diagonally with respect to the rail, consequently any inward turning movement of the tongue results in the jaws 13 and 14 being forced further apart and the hold of the jaws on the rail base augmented. The application of the anchor to the rail thus creates a strain in the body of the anchor.

The anchor, as described above, will hold to the rail against creeping forwardly, that is to say, in the direction of the arrow Fig. 2 from the anchor toward the tie against which the anchor bears and the hold which it takes upon the rail base is maintained, as against vibration or other disturbing influences, because the anchor is under strain when in operative position on the rail. Furthermore, the anchor will hold the rail against creeping in the opposite direction as when the anchor itself is held by the ballast or a tie.

One of the advantages of the device is that it can be used on rails, the bases of which have somewhat different contours. The fact is that the anchor has to be strained when applied to the rail makes its use possible on rails having bases somewhat narrower than the maximum width of base for which the device is designed. The forcing apart of the jaws 13 and 14 necessary in applying the device to the rail and the adjustability of the locking tongue take care of any slight differences in width of a given rail base. The anchor, preferably, is designed so that the jaws take a tight hold on the rail base flanges when the tongue is in the position shown in Figures 1 and 2. Since the jaw 13 stands diagonally with respect to the rail base, the hold of the jaws on the rail base will be tightened as the tongue is turned toward the rail. The forcing apart of the jaws 13 and 14 results in the vertical walls of the opposing jaws being forced into biting engagement with the vertical edges on opposite sides of the rail base; consequently the jaws need not necessarily grip both top and bottom surfaces of the base flanges and therefore may be made slightly loose fitting in that respect, thereby accommodating rail bases of different thickness or having upper surfaces of different slope.

The modified construction shown in Figs. 5 to 8 inclusive differs from that shown in the preceding figures, generally speaking, only in respect to the shape of the portions termed the intervening web portions and in the manner of applying it to the rail. In the modified construction the free ends of the web portions 25 are spread apart and the locking tongue 17 brought around into engagement with the side of the jaw 13^a by any suitable means and the web portions are curved all substantially as shown in Fig. 7 before the device is applied to the rail. The jaws 12^a are formed with beveled surfaces 26 to facilitate application of the anchor to the rail.

The modified anchor is applied to the rail as follows: It is placed under the rail with the jaws 13^a and 14^a engaging the edge of one of the base flanges, this position being shown in Fig. 8. The other end of the anchor is then raised into the position shown in dotted lines Fig. 8, and, by means of a track bar 27 inserted between the inner surface of the anchor at that end and the edge 5 of the other base flange, the anchor is elongated sufficiently to permit the beveled surfaces 26 to ride over and the jaws 12^a to snap into engagement with the edge of the base flange, as shown in full lines in Fig. 8, 10 also in Figs. 5 and 6. This operation eliminates substantially all curvature from the web portions 25 and ordinarily the jaws of the anchor will have a tight binding grip 15 on the rail base. The locking tongue is adjustable and if there should be any looseness 20 in the engagement of the anchor with the rail base after being applied as aforesaid, or if any such looseness should develop, as by corrosion, it may be eliminated by turning 25 the tongue inward toward the rail thereby forcing the jaws 13^a and 14^a further apart and augmenting the hold or grip of the 30 jaws on the rail base. This modified construction has greater capacity for accommodating 35 rail bases of varying widths and contours than the construction first described because in the modified construction the jaw 13^a may project out further and the tongue 17^a placed initially at a greater angle 40 to the rail base flange, since the members 25 do not have to be brought into parallelism to apply the device to the rail, consequently the adjustable tongue has a greater range of usefulness in augmenting the hold of the 45 jaws on the rail base.

I do not claim specifically herein the form of the invention shown in Figs. 5 to 8 inclusive. The specific features of this form of the invention are claimed in my co-pending divisional application Serial No. 544, 45 493 filed March 17, 1922.

I claim:

1. A one piece rail anchor comprising a rail base embracing member provided at one 50 end with means for engaging one side of a rail base and at the other end with means for engaging the other side of the rail base at two points, said second mentioned engaging means being adapted to be forced apart whereupon the grip of said engaging means on the rail base is made effective, and means adapted to maintain said engaging means in such gripping position.

2. A one piece rail anchor comprising a 55 rail base embracing member provided at one end with means for engaging one side of a rail base and at the other end with means for engaging the other side of the rail base at two points, said second mentioned engaging

means being adapted to be forced apart 65 whereupon the grip of said engaging means on the rail base is made effective, and means adapted to maintain said second mentioned engaging means in such forced apart position. 70

3. A rail anchor provided at one end with means for engaging one side of a rail base and at the other end with jaws for engaging the other side of the rail base, said jaws being adapted to be forced apart whereupon the grip thereof and of said engaging means on the rail base is made effective, and means adapted to be driven between said jaws to maintain them in such forced apart position. 75

4. A one piece rail anchor comprising a rail base embracing member provided at one end with means for engaging one side of a rail base and at the other end with jaws for engaging the other side of the rail base, 80 said jaws being adapted to be forced apart whereupon the grip thereof and of said engaging means on the rail base is made effective, and means associated with one of said jaws and adapted to bear against the other jaw to maintain said jaws in such forced apart position. 85

5. A rail anchor provided at one end with means for engaging one side of a rail base and at the other end with jaws for engaging the other side of the rail base, said jaws being adapted to be forced apart whereupon the grip thereof and of said engaging means on the rail base is made effective, and a locking tongue adapted to maintain said 90 jaws in such forced apart position. 95

6. A rail anchor provided at one end with means for engaging one side of a rail base and at the other end with jaws for engaging the other side of the rail base, said jaws being adapted to be forced apart whereupon the grip thereof and of said engaging means on the rail base is made effective, and a tongue associated with one of said jaws and adapted to bear against the other jaw to maintain said jaws in such forced apart position. 100 105

7. A rail anchor provided at one end with means for engaging one side of a rail base and at the other end with means for engaging the other side of the rail base at two points, a tie abutment adjacent a portion of said second mentioned engaging means, said second mentioned engaging means being adapted to be forced apart whereupon the grip of said engaging means on the rail base is made effective, and means adapted to maintain said engaging means in such gripping position. 110 115

8. A rail anchor provided at one end with means for engaging one side of a rail base and at the other end with jaws for engaging the other side of the rail base, said jaws be- 120 125

- ing adapted to be forced apart whereupon the grip thereof and of said engaging means on the rail base is made effective, means adapted to maintain said jaws in such forced apart position and a tie abutment on the end of the anchor provided with the last mentioned jaws.
9. A rail anchor comprising a pair of bars adapted to extend under the base of a rail and connected together at one end, one of said bars at that end having means for engaging one side of the rail base, each bar at the other end having means for engaging the other side of the rail base, the free ends of said bars being adapted to be forced apart whereupon the grip of said engaging means on the rail base is made effective, and means adapted to be driven between said bars to maintain said engaging means in such gripping position.
10. A rail anchor comprising a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means and said jaws on the rail base is made effective, and means adapted to be driven between said bars to maintain the bars and the jaws thereon in such forced apart position.
11. A one piece rail anchor comprising a rail base embracing member formed with a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means and said jaws on the rail base is made effective, and means associated with one of said bars and adapted to bear against the other bar to maintain the bars and the jaws thereon in such forced apart position.
12. A rail anchor comprising a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means and said jaws on the rail base is made effective, and a locking tongue associated with one of said bars and adapted to bear against the other bar to maintain the bars and the jaws thereon in such forced apart position.
13. A rail anchor comprising a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means on the rail base is made effective, and an extension on the free end of one of said bars and adapted to bear against the other bar to maintain the bars and the jaws thereon in such forced apart position.
14. A rail anchor comprising a pair of bars adapted to extend under the base of a rail and connected together at one end, one of said bars at that end having means for engaging one side of the rail base, each bar at the other end having means for engaging the other side of the rail base, a tie abutment on one of said bars adjacent its said jaw, the free ends of said bars being adapted to be forced apart, whereupon the grip of said engaging means on the rail base is made effective, and means adapted to maintain said engaging means in such gripping position.
15. A rail anchor comprising a pair of bars adapted to extend under the base of a rail and connected together at one end, one of said bars at that end having means for engaging one side of the rail base, each bar at the other end having a jaw for engaging the other side of the rail base, a tie abutment on one of said bars adjacent its said jaw, the free ends of said bars being adapted to be forced apart whereupon the grip of said engaging means and said jaws on the rail base is made effective, and means adapted to maintain the bars and the jaws thereon in such forced apart position.
16. A one piece rail anchor comprising a rail base embracing member provided at one end with means for engaging one side of a rail base and at the other end with means for engaging the other side of the rail base at two points, said second mentioned engaging means being adapted to be forced apart whereupon the grip of said engaging means on the rail base is made effective, and adjustable locking means adapted to maintain said engaging means in such gripping position.
17. A rail anchor provided at one end with means for engaging one side of a rail base and at the other end with jaws for engaging the other side of the rail base, said jaws being adapted to be forced apart whereupon the grip thereof and of said engaging means on the rail base is made effective, and an adjustable locking tongue adapted to maintain said jaws in such forced apart position.
18. A one piece rail anchor comprising a rail base embracing member providing a

- pair of bars adapted to extend under the base of a rail and connected together at one end, one of said bars at that end having means for engaging one side of the rail base, each bar at the other end having means for engaging the other side of the rail base, the free ends of said bars being adapted to be forced apart whereupon the grip of said engaging means on the rail base is made effective, and adjustable locking means adapted to maintain said engaging means in such gripping position.
19. A one piece rail anchor comprising a rail base embracing member providing a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means and said jaws on the rail base is made effective, and adjustable locking means adapted to maintain the bars and the jaws thereon in such forced apart position.
20. A rail anchor comprising a pair of bars, one of which extends diagonally under the rail base when the anchor is in operative position thereon, said bars being connected together at one end, one of said bars at that end having means for engaging one side of the rail base, each bar at the other end having means for engaging the other side of the rail base, the free ends of said bars being adapted to be forced apart whereupon the grip of said engaging means on the rail base is made effective, and an extension on the free end of one of said bars and adapted to bear against the other bar to maintain the bars and the engaging means thereon in such forced apart position, said extension as it is forced inward tending to increasingly force said bars apart and augment the hold of said engaging means on the rail base.
21. A rail anchor comprising a pair of bars, one of which extends diagonally under the rail base when the anchor is in operative position thereon, said bars being connected together at one end, one of said bars at that end having means for engaging one side of the rail base, each bar at the other end having means for engaging the other side of the rail base, a tie abutment on one of said bars adjacent its free end, the free ends of said bars being adapted to be forced apart whereupon the grip of said engaging means on the rail base is made effective, and an extension on the free end of one of said bars and adapted to bear against the other bar to maintain the bars and the engaging means thereon in such forced apart position, said extension as it is forced inward tending to increasingly force said bars apart and augment the hold of said engaging means on the rail base.
22. A rail anchor provided at one end with means for engaging one side of a rail base and at the other end with means for engaging the other side of the rail base at two points, said second mentioned means being adapted to be forced apart whereupon the grip of said means on the rail base is made effective, and means adapted to maintain said rail engaging means in such gripping position, the rail engaging means at one end of the anchor being formed with a beveled surface, adapted to ride over the rail base during application of the anchor to the rail.
23. A rail anchor provided at one end with means for engaging one side of a rail base and at the other end with jaws for engaging the other side of the rail base, said jaws being adapted to be forced apart whereupon the grip thereof and of said engaging means on the rail base is made effective, and a tongue associated with one of said jaws and adapted to bear against the other jaw to maintain said jaws in such forced apart position, said tongue being formed with a beveled surface adapted to facilitate its positioning in such bearing engagement.
24. A rail anchor comprising a pair of bars adapted to extend under the base of a rail and connected together at one end, one of said bars at that end having means for engaging one side of the rail base, each bar at the other end having a jaw for engaging the other side of the rail base, the free ends of said bars being adapted to be forced apart whereupon the grip of said engaging means and said jaws on the rail base is made effective, and a locking tongue associated with one of said bars and adapted to bear against the other bar to maintain the bars and the jaws thereon in such forced apart position, said tongue and the bar against which it bears being formed with beveled surfaces adapted to facilitate positioning of said tongue in such bearing engagement.
25. A one-piece rail anchor comprising a metal member bent to the shape of a V, means at the apex of said member to engage one side of a rail base, and means at the other end on each leg of said V to engage the other side of the rail base, and an extension on one of said legs adapted to force said legs apart whereby said rail engaging means are forced into effective holding engagement with said rail base.
26. A one-piece rail anchor comprising a metal member bent to the shape of a V, means at the apex of said member to engage one side of a rail base and means at the other end on each leg of said V to engage the other side of the rail base, and an adjust-

able locking tongue on one of said legs adapted to bear against the other leg to force said legs apart whereby said rail engaging means are forced into effective holding engagement with said rail base.

27. A one piece rail anchor comprising a metal member bent to the shape of a V, means at the apex of said member to engage one side of a rail base and means at the other end on each leg of said V to engage the other side of the rail base, and an extension on one of said legs adapted to force said legs apart, said extension as it is forced inward tending to increasingly force said legs apart and augment the hold of said engaging means on the rail base.

28. A one piece rail anchor comprising a metal member bent to the shape of a V, each leg of which is provided with means to engage opposite sides of the rail base, and an extension on one of said legs adapted to force said legs apart whereby said rail engaging means are forced into effective holding engagement with said rail base.

29. A one piece rail anchor comprising a metal member bent to the shape of a V, means at the apex of said member to engage one side of a rail base and means at the other end on each leg of said V to engage the other side of the rail base, a tie abutment on one of said legs, and an extension on one of said legs adapted to force said legs apart whereby said rail engaging means are forced into effective holding engagement with said rail base.

30. A one piece rail anchor comprising a metal member bent to the shape of a V, means at the apex of said member to engage one side of a rail base and jaws at the free ends of the legs of said V to engage the other side of the rail base, and an extension on one of said legs adapted to force said legs apart whereby said rail engaging means and said jaws are forced into effective holding engagement with said rail base, said jaws each being formed with beveled surfaces adapted to ride over the rail base when the anchor is applied to the rail.

31. A rail anchor comprising a pair of bars adapted to extend under the base of a rail and connected together at one end, one of said bars at that end having means for engaging one side of the rail base, each bar at the other end having means for engaging the other side of the rail base, said bars being adapted to be brought into substantially parallelism and the free ends thereof then forced apart in applying the anchor to the rail, and means adapted to be driven between said bars whereby said rail engaging means are maintained in effective holding engagement with the rail base.

32. A rail anchor comprising a pair of bars adapted to extend under the base of a rail and connected together at one end, one

of said bars at that end having means for engaging one side of the rail base, each bar at the other end having means for engaging the other side of the rail base, said bars being adapted to be brought into substantially parallelism and the free ends thereof then forced apart in applying the anchor to the rail, and manually adjustable means whereby said rail engaging means are maintained in effective holding engagement with the rail base.

33. A one piece rail anchor comprising a metal member bent to the shape of a V, means at the apex of said member to engage one side of a rail base and means at the other end on each leg of said V to engage the other side of the rail base, said legs being adapted to be brought into substantial parallelism and the free ends thereof then forced apart in applying the anchor to the rail, and an extension on one of said legs and adapted to bear against the other leg to maintain the legs in such forced apart position, said extension as it is forced inward tending thereby to increase the grip of said engaging means on the rail base.

34. A rail anchor provided at one end with means for engaging the rail base at one side thereof and at the other with jaws for engaging the other side of the rail base at two points, said jaws being adapted to be forced apart by straining the anchor to produce a grip of the anchor on the rail.

35. A resilient rail anchor provided at one end with means for engaging the rail base at one side thereof and at the other jaws for engaging the other side of the rail base at two points, said jaws being adapted to be forced apart by straining the anchor to force them into gripping engagement with the rail.

36. A rail anchor provided at one end with means for engaging the rail base at one side thereof and at the other for engaging the other side of the rail base at two points, said anchor being adapted to be strained in the application thereof to the rail to separate said last mentioned points of engagement so as to produce a grip of the anchor on the rail and for positively maintaining said points of engagement in the separated position.

37. A rail anchor comprising two bars to extend under the base of a rail from edge to edge, one of said bars being formed with means for engaging the rail base at one edge and said bars being formed at their opposite ends with jaws for engaging the other edge of the rail base at spaced points, said jaws being adapted to be forced apart by straining the anchor to produce a grip of the device on the rail.

38. A rail anchor comprising two resilient bars to extend under the base of a rail from edge to edge, one of said bars being formed

with means for engaging the rail base at one edge and said bars being formed at their opposite ends with jaws for engaging the other edge of the rail base at spaced points, 5 said jaws being adapted to be forced apart by straining the anchor so as to produce a spring grip of the anchor on the rail. 39. A resilient rail anchor comprising two bars adapted to extend under the base of a 10 rail from edge to edge and members inter-

vening between said bars at opposite ends of the anchor, one of said bars being provided with means for engaging one edge of the rail base and the bars being provided at the other end of the anchor with separate 15 means adapted to be forced apart, in the application of the anchor to the rail, for engaging the other edge of the rail base.

ROLANDIS A. BLAIR.
